Geo. Kimmel. ATTORNEY.

UNITED STATES PATENT OFFICE.

NORMAN W. NUTT, OF TRENTON, NEW JERSEY.

FUSE-PLUG-CAP ASSEMBLY.

Application filed January 25, 1927. Serial No. 163,468.

This invention relates to a fuse plug cap assembly, and has for its object to provide, in a manner as hereinafter set forth, a fuse plug cap assembly in which the construction thereof is such that the cap member of a plug is secured to the plug body by a frictional forcing lock which prevents separation and rotation of the cap member relative to the plug body.

It has been the practice up to the present time to lap the cap members on or to make projections on the different parts to prevent separation or rotation, but this method is expensive and somewhat unsatisfactory, as the joining method has a tendency to loosen, and to secure satisfactory results it has been in a number of cases necessary to cement the parts to prevent any loosening thereof.

A further object of the invention is to provide, in a manner as hereinafter set forth, a fuse plug cap assembly having the insulating plug body thereof formed with a tapered cap member receiving terminal portion or extremity provided at its point of largest diameter with an annular peripheral shoulder acting as an abutment for the cap member and further greatly facilitating the manufacturing of the insulating plug body.

Further objects of the invention are to provide, in a manner as hereinafter set forth a fuse plug cap assembly including means for joining the cap member to the plug body in a simple, efficient and expeditious manner, and further to provide a fuse plug cap assembly which is strong, durable, compact, readily assembled, and comparatively inexpensive to manufacture.

With the foregoing and other objects in view the invention consists of the novel construction, combination and arrangement of parts as hereinafter more specifically described, and illustrated in the accompanying drawings, wherein is shown an embodiment of the invention, but it is to be understood that changes, variations, and modifications can be resorted to which fall within the scope of the claims hereunto appended.

In the drawings wherein like reference characters denote corresponding parts throughout the several views:

Figure 1 is an elevation of a fuse plug cap assembly in accordance with this invention.

Figure 2 is a sectional elevation of the outer section or part of the plug body and

further illustrating a cap member in position.

Figure 3 is a top plan view of the fuse plug cap assembly.

Figure 4 is a section on line 4—4 Figure 2.

Figure 5 is a view similar to Figure 2 of a modified form.

Figure 6 is a section on line 6—6 Figure 5.

As is well known, the body of the fuse plugs, now generally employed, is constructed of insulation material and formed of a hollow outer part or section open at each end and a hollow inner part or section closed at its inner end. The sections are secured together in abutting relation, preferably by cementitious material. The outer section of the plug body is indicated at 1 and the inner section thereof at 2 in Figure 1.

The invention forming the subject matter of this application relates solely to the outer terminal portion or extremity of the plug body, or rather the outer terminal portion or extremity of said outer section 1, in connection with a cap member referred to by the reference character 3. The cap member 3 is utilized for maintaining a transparent closure 4 in position within the outer end of the section 1. Said closure permits of viewing the interior of the fuse plug when required. The cap member 3 is constructed from any suitable, slightly yieldable material, preferably thin metal.

The section 1 has its outer periphery at the outer terminal portion or extremity 6, tapered as at 5, and at the point of largest diameter of the tapered outer face of the outer terminal portion 6, an annular shoulder 7 is formed which constitutes an abutment. The outer end edge of the section 1 is rabbeted, as at 8, to provide a seat for a transparent closure 4, and when the latter is in position the outer face thereof is flush with the non-rabbeted part of the outer end edge of the section 1. The tapered outer face 5 of the terminal portion 6, from the shoulder 7 to the outer edge of the section 1, is knurled, corrugated or ribbed throughout. The high parts of the corrugations or the ribs are indicated at 9 and which are disposed throughout at an inclination and the inclination is inwardly from the shoulder 7 to the outer end edge of the section 1. The high part of the corrugations or the ribs 9 are arranged in

wardly with respect to the outer peripheral edge of the shoulder 7. Or in other words the transverse width of the shoulder 7 is greater than the thickness of the high part 5 or rib 9.

The cap member 3 comprises a flat annulus 10 and a rim 11. The annulus 10 has its inner diameter materially less than the diameter of the closure 4. The annulus 10 merges into the rim 11, and is tapered, extends inwardly and is of a diameter to frictionally engage the ribs or high parts of the corrugations 9 to distort the rim and set up a frictional forcing lock, whereby the cap 15 member 3 will be secured to the section 1 in a manner to prevent the separation and rotation of such member relative to the section 1. The diameter of the rim 11 is slightly less than the outer diameter of the shoulder 7 20 and the latter provides an abutment for the edge of the rim 11.

The construction shown in Figures 5 and 6 is the same as that shown in Figures 3 and 4, with this exception that the tapered outer 25 face 12 of the outer terminal portion or extremity 13 of the section 1 is not corrugated, ribbed or knurled, but is plain. Otherwise than that as stated the construction shown 30 in Figures 5 and 6 is the same as that shown in Figure 2 and corresponding parts are provided with like reference characters.

The transparent closure 4 is constructed 35 of insulation material, and the annulus 10 of the cap member 3 overlaps the marginal portion of the closure 4 for the purpose of retaining the closure on its seat.

It is thought the many advantages of a 40 fuse plug cap assembly, in accordance with this invention, can be readily understood, and although the preferred embodiment of the invention is as illustrated and described, yet it is to be understood that changes in the 45 details of construction can be had which will fall within the scope of the invention as claimed.

What I claim is:

1. In a fuse plug cap assembly an insulating 50 fuse plug body having a tapered extremity and an annular shoulder at the point of largest diameter of said extremity, said tapered extremity being serrated.

2. An insulating body for fuse plugs having a serrated tapered extremity formed

with an extending shoulder, and a cap member secured to such extremity by a frictional 55 forcing lock.

3. An insulating body for fuse plugs having a serrated tapered extremity provided with an extended shoulder, a transparent insulating closure mounted in said extremity, 60 a cap member mounted on said extremity and secured therewith by a frictional forcing lock, said cap member abutting said shoulder and overlapping said closure.

4. An insulating body for fuse plugs having a serrated tapered extremity provided with an extended shoulder, a transparent insulating closure mounted in said extremity, 65 a cap member mounted on said extremity and secured therewith by a frictional forcing 70 lock, said cap member abutting said shoulder and overlapping said closure.

5. A fuse plug cap assembly comprising an insulation plug body having a part of its periphery tapered and further having a 75 peripheral shoulder at one end of said part, a cap member frictionally engaging with said part, and a transparent portion mounted in the plug body and overlapped by said member, and the said tapered peripheral so part being serrated.

6. A fuse plug cap assembly comprising an insulation plug body having a part of its periphery tapered and further having a 85 peripheral shoulder at one end of said part, a cap member frictionally engaging with said part, and a transparent portion mounted in the plug body and overlapped by said member, and the said tapered peripheral part 90 being serrated, and said shoulder extended from said part and of annular contour.

7. A fuse plug cap assembly comprising an insulating plug body having its outer end edge formed with a rabbet and further having the outer periphery of its outer terminal portion serrated and tapered, said body further formed with a peripheral shoulder at the inner end of said tapered periphery, a transparent closure mounted in said rabbet, and a tapered cap member overlapping the closure, abutting said shoulder and secured with said serrated periphery by a frictional 100 forcing lock.

In testimony whereof, I affix my signature hereto.

NORMAN W. NUTT.
